UNITED STATES PATENT OFFICE.

CHARLES A. POTTER, OF PROVIDENCE, RHODE ISLAND, ASSIGNOR TO THE AMERICAN SHIP WINDLASS COMPANY, OF SAME PLACE.

LOCKING-GEAR FOR WINDLASSES.

SPECIFICATION forming part of Letters Patent No. 371,853, dated October 18, 1887.

Application filed December 24, 1886. Serial No. 222,520. (No model.)

To all whom it may concern:

Be it known that I, CHARLES A. POTTER, a citizen of the United States, residing at Providence, in the county of Providence and State of Rhode Island, have invented certain new and useful Improvements in Locking-Gear for Windlasses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to certain new improvements in locking-gear for windlasses, the same consisting, essentially, in the combination, with a loosely-mounted wild-cat having a notched rim, of a driving-head having one or more locking-keys radially arranged therein, and a loosely-mounted disk or ring having one or more cam-shaped or eccentric projections formed on its inner face, adapted to engage and actuate said locking-keys, all as will be more fully hereinafter set forth and claimed.

The object of my invention is to simplify the construction of ships' windlasses, more particularly the portion adapted to lock and unlock the wild-cat, the improved device being of the "positive" type, as contradistinguished from a "friction-lock," which latter necessarily involves the employment of a greater number of working parts.

The accompanying drawings illustrate the improvement hereinafter claimed, Figure 1 thereof representing a reduced view (in elevation) of a pump-brake windlass provided with my improved locking-gear. Fig. 2 is an enlarged longitudinal sectional view taken through the center of the port wild-cat, driving-head, &c., the wild-cat (on chain-wheel) being locked, as in taking in the cable. Fig. 2½ is a partial sectional view showing the relative position of the parts with the key withdrawn from the wild-cat, the latter then being adapted to freely revolve upon the shaft, as in paying out the cable. Fig. 3 is an end view corresponding to Fig. 2, a portion of the driving-head, &c., being broken away to show the locking-key. Fig. 4 is a plan view

of the same. Fig. 5 is an end view of the locking disk or ring, showing an eccentrically-arranged projection formed on its face. Fig. 6 is a detached perspective view of the locking or block key adapted to engage said eccentric projection, and Figs. 7 and 8 represent side views of the block-key provided with a flat spring.

The following description relates more particularly to the construction of the specific device represented in the drawings.

W in the drawings designates the wild-cat as a whole, loosely mounted on the windlass-shaft s, the same having lugs l, adapted to engage the chain-cable, and a circumferential groove, g, adapted to receive a brake-band, b², as usual. The overhanging rim E (in which is formed said groove g) is further extended and provided with a series of (preferably) elongated openings, F, cut into the face thereof, adapted to receive about one-half the upper portion of the locking-key.

H indicates the driving-head, the same being rigidly secured to the windlass-shaft and adjacent to the wild-cat, as usual. The outer portion of the driving-head is offset, (see Fig. 2½,) thereby permitting the said extended portion of the wild-cat's rim to revolve therein. The outer diameters of the rim E and the head H are substantially the same. As drawn, there are two oppositely-located pockets or openings, F', formed in the rim of the driving-head, which communicate with the space enclosed by the two vertical ribs a¹. (See Figs. 2 and 3.) The continuity of the head opposite the pocket F' is maintained by the metal ties p.

R indicates the operating-disk or locking-ring, the same being bored out, as at h², to loosely fit the turned portion h of the driving-head's hub, a collar, n, being secured to the windlass-shaft, to prevent longitudinal movement of the loosely-mounted locking-ring. To the periphery of the locking-ring are secured a number of operating-handles, r, intermediate of which, if desired, are formed radial sockets m, adapted to receive a lever, l'. The latter is used when greater purchase or leverage is required to withdraw the locking-key. Upon the front face of the disk or ring R, and near the rim, are formed oppositely-arranged

eccentric-shaped ribs or projections *c*, each of which extends about half-way around the disk, the amount of eccentricity or "throw" thereof being substantially equal to the thickness of the rim *E* of the wild-cat. Said ribs are adapted to simultaneously operate two locking-keys. In lieu of the eccentric rib, the latter may be cam-shaped.

A indicates the locking-key, the same being nearly or quite square in cross-section and having the two ears *c*⁶ *c*⁵, Fig. 6, formed on its lower portion, the adjacent faces of which are slightly rounded. The space *c*⁴ between the said ears is adapted to freely receive a rib, *c*, of the locking-ring, before described.

Assuming, now, a ship's windlass to be provided with my improved locking-gear, the operation of withdrawing the key from the loosely-mounted wild-cat would be as follows: Referring to Figs. 2, 3, and 4 of the drawings, the several parts are indicated in the locked position the same corresponding to that in "taking in" the chain or hoisting the anchor, &c. Now, as drawn, upon rotating the loosely-mounted operating-disk *R* in the arrow direction to its limit by means of the handles *r*, both keys *A* are simultaneously drawn down out of the openings *F*' of the wild-cat and wholly into the driving-head, the keys, &c., then appearing as indicated in Fig. 2¹, the wild-cat thereby being in position to pay out the chain, when desired. Its control is effected by a brake-band, *b*², as usual; or the windlass may now be used independently of the wild-cats, as in warping, hoisting sails, &c., as common to mechanism of this class. In Fig. 1 brakes *b* are employed to operate the windlass, as usual. Gipsy ends or heads *e* are secured to the ends of the windlass-shaft, for obvious purposes.

The series of openings *F*, formed in the face of the rim *E* of the wild-cat, are elongated for the purpose of more readily receiving the upper ends of the locking-keys.

A spring, *s*, Figs. 7, 8, may be attached to the key *A*, in order to better retain the latter in position, and at the same time prevent its "rattling." For apparent reasons, the locking-ring may be cut through its center and provided with ears *c*². The two halves are fastened together by bolts, as indicated by dotted lines in Fig. 5.

In many of the locking devices of windlasses heretofore made the same have been so constructed and arranged that the locking-keys (or shoes, if frictionally connected) are nearly or quite concealed. Such devices are obviously a positive disadvantage.

In a windlass combining my present invention a person at a glance may ascertain whether the wild-cat is locked to or disconnected from the driving-head, thereby enabling the operator to act promptly when occasions demand immediate action, and possibly preventing confusion and averting the loss of the vessel.

The wild-cat and driving-head may, without departing from the spirit of the invention,

be constructed and arranged so as to reduce the distance between the bits—that is to say, the rim *E* of the wild-cat may have a series 70 of key-engaging lugs or notches formed on the inner periphery thereof, in lieu of the several edge openings *F*', in which event the flange of the driving-head *H* is made somewhat smaller in its outer diameter, so that the said 75 rim *E* is adapted to pass over the flange and freely revolve. The locking-keys at the same time are necessarily shorter.

It is evident that one locking-key may be used to connect the wild-cat to the head, 80 although I prefer to employ two.

It is further obvious that the device shown is readily adapted to be combined in other types of windlasses—as, for example, capstan, crank, steam windlasses, &c.

I would not be understood as claiming, broadly, the simultaneous operation of one or more locking-keys by means of the partial rotation of a loosely-mounted disk or ring.

What I do claim is—

1. The combination, with a loosely mounted wild-cat having an overhanging rim provided with openings or pockets adapted to engage a locking-key, of a driving-head rigidly secured to a driving-shaft, one or more radially-guided locking-keys mounted in said driving-head, and a loosely-mounted ring or disk having means for rotating the same, and, further, having one or more cam-shaped ribs formed on its face adapted to engage and simultaneously operate said locking keys in endwise directions, substantially as hereinbefore set forth.

2. In a windlass, the combination, with a loosely-mounted wild-cat, *W*, having an overhanging notched rim, *E*, of the driving-head *H*, rigidly secured to the windlass-shaft *S*, having radial oppositely-located openings *F*', locking-keys *A*, loosely mounted in said openings *F*', each having a space, *c*⁴, formed in its outer face transversely of the windlass-shaft, and the loosely-mounted locking disk or ring *R*, having oppositely-located cam-shaped ribs *c* formed on its face, adapted to engage said locking-keys, and, further, having means for 110 rotating it by hand, substantially as shown, and hereinbefore described.

3. The combination, with a loose wild-cat, a rigidly-secured driving-head, and locking-keys loosely mounted and guided in said driving-head, adapted to move endwise and lock the wild-cat thereto, of the loosely-mounted locking disk or ring having an eccentric or cam shaped face engaging said locking-keys to simultaneously operate them by the partial 125 rotation of the disk, substantially as hereinbefore described.

In testimony whereof I affix my signature in the presence of two witnesses.

CHARLES A. POTTER.

Witnesses:

CHARLES HANNIGAN,
WM. R. DUTEMPLE.
